PHILIP POVLOTZKY, OF CHICAGO, ILLINOIS.

STARTING DEVICE FOR INTERNAL-COMBUSTION ENGINES.

1,234,563.

Specification of Letters Patent.

Patented July 24, 1917.

Application filed November 27, 1916. Serial No. 133,621.

To all whom it may concern:

Be it known that I, PHILIP POVLOTZKY, a citizen of the United States, residing at Chicago, in the county of Cook and State of Illinois, have invented new and useful Improvements in Starting Devices for Internal-Combustion Engines, of which the following is a specification.

This invention relates to that class of starting devices for internal-combustion engines in which a spring motor is employed.

The invention has for its object to provide a novel and improved mechanism whereby the spring of the motor is rewound by the engine after the same has been started, and also to provide novel and improved means for preventing overwinding of the spring, the winding mechanism being automatically uncoupled after the spring has been wound to a predetermined degree.

Other objects and advantages of the present invention will be pointed out in the detailed description appearing hereinafter, and in order that the same may be better understood, reference is had to the accompanying drawings forming a part of this specification.

In the drawings—

Figure 1 is a plan view of the mechanism; Fig. 2 is a side elevation thereof;

Fig. 3 is an enlarged end view;

Fig. 4 is a central longitudinal section on the line 4—4 of Fig. 3;

Fig. 5 is a face view, partly broken away, of a worm wheel;

Fig. 6 is a perspective view of one of the elements of the mechanism;

Fig. 7 is a perspective view showing the opposite side of said element;

Fig. 8 is a perspective view of a clutch member;

Fig. 9 is a perspective view of a co-operating clutch member;

Fig. 10 is a perspective view of certain parts of the mechanism, disconnected, and

Fig. 11 is a perspective view showing the manner in which the spring is anchored at its ends.

Referring specifically to the drawings, 15 denotes a suitable housing inclosing the starting mechanism, said housing being provided with end flanges 16 and 17, respectively, to which are secured, by bolts 20, end plates 18 and 19, respectively, for closing the 55 ends of the housing. In the housing is a transverse partition 21 enlarged at the cen-

ter and formed with a bearing 22 for a spring-actuated driving shaft 23. This shaft is also supported in a bearing 24 formed on the end plate 19. Between the 60 partition 21 and the end plate 19 is located a spring 25, the same being coiled around the shaft 23. One end of the spring is fixed to the shaft 23 by being inserted into a longitudinal notch 26^a in the latter, and the 65 other end of the spring is secured to the wall of the housing 15 by being inserted into an undercut groove 27^a therein, said grooved portion of the housing being reinforced as indicated at 28^a.

On that end of the shaft which is inclosed in the housing 15 is mounted a worm wheel 27 having a hub 26 to receive said shaft, the worm wheel being loose on the shaft. In mesh with the worm wheel 27 is a worm 28 75 journaled in a bearing 28^b on the outside of the housing 15. The worm has a bevel gear 29 at one end, and at its opposite end a reduced angular portion 28^c for the application of a wrench or other tool when it is 80 desired to turn the worm by hand. The bevel gear 29 is in mesh with a bevel gear 30, the shaft 32 of which is journaled in a bearing 31 on the housing 15. On the shaft 32 is fixed a spur gear 33 which meshes 85 with an idler pinion 34, the latter in turn meshing with a pinion 35. The pinion 34 has a shaft 36 supported in the end plate 18, and the pinion 35 is loose on a starting shaft 37 passing through the end plate 18. It will 90 be seen by the foregoing that the motion of the pinion 35 is transmitted through the pinion 34, gear 33, gears 30 and 29 and worm 28 to the worm wheel 27 at a greatly reduced speed. The shaft 37 has a suitable 95 driving connection with the engine crank shaft, and the gearing just described is provided for the purpose of winding the spring 25 as will be described more fully herein-after.

Alongside one face of the worm wheel 27 is a rotatable member in the form of a large disk 38 having a hub 38^a provided with an external annular groove 39, the disk being loose on the hub 26 and also extending over and seating loosely on the outside of the bearing hub 22. The disk is loosely mounted on these hubs in order that it may be slid in the direction of the length of the shaft 23 toward and from the worm wheel 27. The 110 disk 38 has two diametrically opposite latch pins 40 extending outward from one of its

faces and passing through apertures 41 in the web of the worm wheel 27, the length of the pins being such that they may project from the web of the worm wheel on the side opposite the side where the disk 38 is positioned, and upon backing the disk away from the worm gear the pins are retracted. The disk 38 is shifted by means of a fork 42 straddling the hub 38^a in the groove 39. The stem 43 of this fork passes through an aperture in the wall of the housing 15 and has on the outside thereof an enlarged head 45 which is made fast to a longitudinally slidable rod 74.

On that side of the worm wheel 27 from which the pins 40 project is located another rotatable member 46 in the form of a large disk having an elongated hub 47 partly supported on the shaft 23, which latter terminates within said hub. This disk has two diametrically opposite peripheral wings 48 pointing in opposite directions, and alternate edges of these wings are recessed to form seats 49 for the pins 40, said seats engaging the pins when the disk 46 is turned and when the pins 40 protrude from the worm wheel 27. The disks 38 and 46, and the worm wheel 27 are now coupled to turn as one, and when the pins are retracted out of the path of the wings 48, the disk 46 is disconnected and is free of the worm wheel.

The outer surface of the hub 47 of the disk 46 is formed with a screw-thread 49^a, and on this threaded portion of the hub is mounted, for travel thereon, a nut 50 which is the hub of a clutch member 51, the co-operating clutch member thereof being shown at 58. The hub 47 has two diametrically opposite keys 52 seating in slots 53 in the periphery of the shaft 23, whereby the disk 46 is fixed on said shaft to turn therewith. To lock the disk 46 against longitudinal movement on the shaft 23 a screw 54 is passed transversely through one side of the hub 47 and into and through the shaft 23, and embedded in a recess 55 in the other side of the hub 47. The rear end of the hub 50 of the clutch member 51 must be gouged out as shown at 56 to permit insertion of the screw 54, and the wall of the housing 15 is apertured at 57 to permit a screw-driver to be inserted to pass into the hub 47 to engage the screw 54, the latter having a nicked end which is sunken below the threads 49^a when the screw is in place. The clutch members 51 and 58 are ordinary cone clutches, the member 51 being entered by the member 58. The clutch member 58 is integral with or fixed to the shaft 37, the latter extending from one side thereof, and from the opposite side of said clutch member extends a short stub shaft 59 having a flanged extremity 60 in proximity to the end of the shaft 23. On the shaft 59 is loosely mount-

ed a collar 61 which is split as shown at 62 to permit mounting. This collar is externally screw-threaded and is screwed into the forward portion of the hub 47, the latter being tapped to correspond to the threads of the collar. The outer end of the collar 61 has a number of teeth forming radial slots 63 in diametrically opposite pairs, a suitable pair of these slots being adapted to receive two correspondingly located studs 64 projecting from the end of the shaft 23. Thus, the collar is locked to the shaft 23. The collar 61 prevents the clutch member 58 from backing and binding against the parts behind it when the clutch member 51 advances. The outer face of the clutch member 58 has a projecting lug 65 near its periphery for a purpose to be presently described.

The pinion 35 which is loosely mounted on the shaft 37 has a rearward hub extension 66, the outer surface of which is angular, and on which is slidably longitudinally a disk 67, said disk also turning with the pinion 35 by reason of the angularity of the hub 66. One side of the disk 67 has a grooved hub 68 which is straddled by a shifting fork 69 projecting through an aperture 70 in the wall of the housing 15, and formed on the outside of the latter with a head 71. The disk 67 has a peripheral lug 72 so positioned that it may engage the lug 65 of the clutch member 58 when the disk 67 is shifted over toward said clutch member. The disk 67 is shifted by the fork 69, and the latter in turn is operated by a rod 73 extending parallel to the rod 74 on the outside of the housing. The parts 67 and 58 form a clutch or coupling between the shaft 37 and the gear 35.

The rods 73 and 74 are slidable in bearings 75 on the outside of the wall of the housing 15, and also through an upward extension 76 of the end flange 17. One end of the rod 73 passes through and is made fast to the fork head 71, and at an intermediate point the rod 74 passes through and is made fast to the fork head 45. It is the function of these two rods to actuate the shifter forks 42 and 69, and each rod is provided with a spring for drawing the same in one direction, the rod 73 to be normally drawn forward by a spring 77, and the rod 74 being drawn, normally, rearward by a spring 78. The rods 73 and 74 pass loosely through notches 78^a in the end plate 19, and the rod 73 terminates in a short reduced portion 79 cut off with a bevel or slant, as shown at 80. The projecting end of the rod 74 takes a sleeve 81 which is free to turn on the rod, but moves with the same when it is shifted longitudinally.

At the end plate 19 the shaft 23 projects, and said projecting end has a pinion 82, which latter may be integral with, or sepa-

rate from and fixed on the shaft. This end plate also has, on the outside, two stub shafts 83 and 84. On the stub shaft 83 is mounted a large spur gear 85 which is in mesh with the pinion 82. On the stub shaft 84 is mounted, for swinging movement, the hub 86 of a cam 87, said hub also having a projecting radial arm 88 and a projecting radial finger 89, said cam, arm and finger projecting in different directions. The cam 87 has a transverse oblique face to bear on the beveled end 80 of the rod 73, so that when said cam swings in one direction, the rod is pushed rearward, said rod being moved in the opposite direction by the spring 77. The arm 88 projects onto the face of the gear 85 into the path of a projecting pin or abutment 90 thereon.

The sleeve 81 mounted on the rod 74 has an integral projecting arm 91 which is connected to the finger 89, the following connection being provided: On a pin 92 passing through the arm 91 is loosely or pivotally connected a stem 93 on which is screwed one end of a tube 94. In the other end of this tube is slidably mounted a headed rod 95 which is linked or loosely connected to the finger 89. The last-mentioned end of the tube is flanged to retain the rod 95 by its head from pulling out of the tube.

Alongside the arm 91 is located a lever 96 which is carried on a pin 97 journaled in a bearing 98 on the plate 19, and retained by a nut or collar 99. This lever is free to be swung outward from the plate 19, it being provided with a guide and stop in the form of a yoke plate 100. The lower end of the lever 96 is apertured as shown at 101 for attachment of a rod or wire to actuate the same from a distance.

Adjacent to the free end of the arm 91 is a detent 102 pivotally mounted at one end on a pin 103 projecting from the plate 19. The free ends of the arms 91 and 102 are opposite each other and in engagement, said ends being shaped to form a lap joint. To hold this joint closed, a spring 105 is anchored to the arm 91 to draw the same against the arm 102, and a weaker spring 106 is anchored to the arm 102, these two springs serving to draw the two arms in opposite directions and thus normally hold their free ends in lapping position. The arm 91 cannot swing beyond the lever 96 as it is held normally thereagainst by the spring 105, and an abutment 107 is provided to limit the outward swing of the arm 102 under the influence of the spring 106.

The lever 96 carries a projecting pin 108 which seats in a recess 109 in the rear edge of the arm 91. Thus, when the lever 96 is swung outward, the pin 108 draws the arm along, and as said arm is fixed to the rod 74, said rod is shifted.

The operation of the apparatus may be summarized as follows: Let it be assumed that the engine is about to be started, and also that the spring 25 has been wound to store sufficient power for the initial revolution of the engine crank shaft to which the shaft 37 is connected. It will be seen that the energy stored in the spring 25 is exerted on the shaft 23 and, in turn, this shaft, through the connections 54 and 52, tends to turn the disk 46, and through the wings 48, by their engagement with the pins 40, the turning tendency is transmitted to the worm wheel 27. However, as the worm wheel 27 is in mesh with the worm 28, the parts are prevented from turning in view of the fact that motion cannot ordinarily be transmitted from a worm wheel to a worm. Hence, it will be seen that the worm gearing prevents the spring 25 from unwinding. At this time the disk 38 and pins 40 are in advanced position and are held from being retracted by the shifter 43 and the rod 74, the parts being held in this position by the spring 78. Also it will be noted that the coupling disk 67 is held spaced from the clutch member 58 by the shifter fork 69, so that the lugs 65 and 72 are out of engagement. The shifter 69 is held in this position by the rod 73, the latter being held retracted by the pin 90 on the gear 85 bearing on the arm 88 which has rocked the cam hub 86 to engage the cam 87 against the beveled end 80 of the rod 73. To start the engine, the lever 96 is drawn outward whereby, through the pin 108, the arm 91 is drawn outward, and through the sleeve 81 the rod 74 is slid in the same direction, this movement of the rod actuating the shifter 43 to draw back the disk 38 and 100 retract the pins 40 so that the latter are now free of the wings 48. The disk 46 is now released, and the spring 25 acting upon the shaft 23 turns said disk 46 as it is coupled to the shaft by the keys 52 and the 105 screw 54. The sudden turn of the disk 46 will, on account of the clutch member 51 being stationary, cause the latter to creep forward into engagement with the clutch member 58, the screw-threads 49 imparting 110 this motion to the clutch member 51. The inertia will be present as long as the disk 46 turns in this direction, so that the clutch member 58 and its shaft 37 will turn, thereby cranking the engine shaft through the connection between the latter and the shaft 37. In the meantime it will be noted that when the shaft 23 started to turn, the spur gear 85, through the pinion 82, was also put in motion, carrying the pin 90 away from 125 the arm 88, and as said arm is now free of pressure, the cam 87 will also be free to rock when impelled by the forwardly drawn rod 73 actuated by the spring 77. In other words, the cam 87 will now not be able to 130

resist the forward stroke of the rod 73. This has the effect of advancing the disk 67 toward the clutch member 58 so that the lug 72 now comes into the path of the lug 65, and the disk 67 is now coupled to the clutch member 58 to turn therewith. However, as the disk 67 is loose on the shaft 37, it turns the pinion 35, and this motion is transmitted through the pinion 34, gears 33, 30 and 29, and worm 28 to the worm wheel 27. 10 However, the worm wheel is now loose on the rotating shaft 23, and being disconnected from the disk 46, said worm wheel, with the disk 38, turns idle in the opposite direction the shaft 37 is turning, without affecting the starting operation.

Now, assuming that the spring 25 unwinds far enough to give the shaft 23 five revolutions, and that the ratio of the gears 20 82 and 85 is one to five, then by the time that five turns have been given the shaft 37, the pin 90 on the gear 85 will have traveled to the dotted position shown in Fig. 3, and again reached the arm 88 and started to 25 push against the same. It will be remembered that when the lever 96 was actuated, the arm 91 was drawn outward through the pin 108. As soon as the arm 91 swung clear of the detent 102, the spring 106 drew the 30 detent inward against the stop 107, and also the arm 91 was locked against return motion by the detent now deflected and positioned behind the same. The swing of the arm 91 was against the tension of the spring 78. 35 While the arm 91 is directly in front of the detent 102, the lever 96 may still be held swung outward if the operator has forgotten to return it, or it may swing back against the end of the housing of its own 40 weight without in any way affecting the operation. With the arm 88 swung upward by the pin 90, it will be seen that this operates to swing the finger 89 downward, and through the parts 95, 94 and 93 the arm 91 45 is pulled in the same direction or rocked on the rod 74 against the tension of the spring 105. This continues until the arm 91 has swung so far inward that it clears the deflected detent 102. With the arm 102 out 50 of its path, the arm 91 will immediately move back with the rod 74 due to the pull of the spring 78 on the latter. During this return movement of the arm 91, said arm will again lap the detent 102, but not completely on account of the pull of the parts 55 93, 94 and 95, and the pull of the spring 106 on the detent.

When the rod 74 was moved back the shifter 43 advanced the pins 40 back into 60 the path of the wings 48 of the disk 46 so that now after the energy of the spring 25 has been spent, and the engine has been started, the shaft 37 operates the worm wheel 27 to wind up the spring. The motion 65 of the shaft 37, for this purpose, is trans-

mitted to the shaft 23 through the pinion 35, pinion 34, gears 33, 30 and 29, worm 28, worm wheel 27, pin 40 and disk 46 to shaft 23. The spring is now rewound, the clutch member 58 turning with the shaft 37, but 70 said clutch member not being coupled to the clutch member 51 as there is no clutching action except when the clutch member 51 is driven by the shaft 23 and advanced toward the clutch member 58. 75

As the spring 25 is now being wound up at a greatly reduced speed, the pinion 82 imparts motion to the gear 85 counterclockwise so that the pin 90 leaves the arm 88 against which it has been pressing, and said 80 pin is carried around back to its original position. The release of the arm 88 by the pin 90 results in the release of the parts 89, 95, 94, 93 and 91 hitherto drawn toward the right. The spring 105, being stronger than 85 the spring 106, will now draw the arm 91, and also the arm 102, to alined and overlapping normal position.

In the meantime the gear 85 is rotating in a counterclockwise direction, while the 90 spring is being wound the five turns, so that the latter are nearly complete when the pin 90 strikes the arm 88 from the right side. As the pin continues to press the arm 88 toward the left, the cam 87 rocks toward the 95 right, forcing the rod 73 inward to push, by means of the shifter 69, the disk 67 out of reach of the lug 65 of the clutch member 58. This disconnects the gears 35, 34, etc., from the shaft 37, and the winding of the spring 100 ceases, and as the shaft 23 now stops turning, the pinion 82 and the gear 85 also stop, with the pin 90 pressed against the arm 88, and the rod 73 retracted against the tension 105 of the spring 77 during the entire time the device is not in use. The cycle of operation 110 is now ended and the device rests wound up awaiting the actuation of the lever 96 for another start.

The partition 21 has recesses 112, one of 110 these being to accommodate the movement of the fork head 45. Both recesses are also useful for driving out the spring 25 from the housing after the end plate 19 is removed. Blows can then be dealt on the 115 inner end of the shaft 23 evenly by applying the tool alternately at one or the other recess 112.

It will be noted that the swinging and sliding movements of the arm 91 have a tendency to twist the spring 105 and the parts 120 93, 94 and 95. The spring, by reason of its flexibility, easily adjusts itself to these movements, but the parts 93, 94 and 95 need lateral as well as vertical flexibility. This 125 is assured by slightly rounding the pin 92 where it is linked to the stem 93, and by making a looped connection between the rod 95 and the finger 89.

The purpose of joining the rod 95 and the 130

tube 94 in loose telescoping fashion, is to prevent binding of the parts if the travel of the pin 90 should result in a push on the rod 95 too far to the left. The function of 5 the rod 95 is only to draw and not to push on the arm 91.

One of the wings 48 has a projecting side pin 113, and the opposite face of the clutch member 51 has a projecting side pin 114.

10 When the disk 46 and the clutch member 51 are assembled, the pins 113 and 114 will be laterally spaced from each other a short distance, and when the spring 25 unwinds to start the engine and the disk 46 turns, the 15 pin 113 will move away slightly from the pin 114. However, when the disk 46 turns in the reverse direction during the winding up of the spring, the tendency will be for the clutch member 51 to close in on the disk 20 in view of the screw-thread 49^a, and be tightened to the disk. This must be prevented in order to obtain the proper operation of the clutch member 51 when the spring unwinds, and hence when the disk 46 25 turns, the pin 113 will strike the pin 114, and prevent the two parts from screwing together, thus leaving the clutch member 51 loose on the threaded portion 49^a of the disk 46.

30 The shifting rod 74 may be connected by a lever or chain to the primer of the carburetor, so that while the engine is being cranked the carburetor will feed a large portion of gasoline for easy starting, and as 35 soon as the rod 74 jumps back the engine will obtain the usual running mixture through the return of the primer.

I claim:

1. In a starting device for internal-combustion engines, a starting shaft, a driving shaft, a spring connected to the driving shaft for turning the same, a worm wheel loose on the driving shaft, a member fixed on the driving shaft, means for coupling 40 said member and the worm wheel together, a clutch member operatively connected to said member, a coöperating clutch member fixed on the starting shaft, a drive gearing between the starting shaft and the worm wheel, 45 said gearing including a worm in mesh with the worm wheel, and means for coupling said gearing to the starting shaft and for uncoupling the same.

2. In a starting device for internal-combustion engines, a starting shaft, a driving shaft, a spring connected to the driving shaft for turning the same, a worm wheel loose on the driving shaft, a member fixed on the driving shaft, means for coupling 50 said member and the worm wheel together, a clutch member operatively connected to said member, a coöperating clutch member fixed on the starting shaft, a drive gearing between the starting shaft and the worm wheel, 55 said gearing including a worm in mesh with the worm wheel, and means for coupling said gearing to the starting shaft and the spring-

the worm wheel and a gear loose on the starting shaft, and means for coupling said loose gear to the starting shaft.

3. In a starting device for internal-combustion engines, a starting shaft, a driving shaft, a spring connected to the driving shaft for turning the same, a worm wheel loose on the driving shaft, a member fixed on the driving shaft, means for coupling 70 said member and the worm wheel together, 75 a clutch member operatively connected to said member, a coöperating clutch member fixed on the starting shaft, a drive gearing between the starting shaft and the worm wheel, said gearing including a worm in 80 mesh with the worm wheel and a gear loose on the starting shaft, and means for connecting said loose gear to the second-mentioned clutch member.

4. In a starting device for internal-combustion engines, a starting shaft, a driving shaft, a spring connected to the driving shaft for turning the same, a worm wheel loose on the driving shaft, a member fixed 85 on the driving shaft, means for coupling said member and the worm wheel together, 90 a clutch member operatively connected to said member, a coöperating clutch member fixed on the starting shaft, a drive gearing between the starting shaft and the worm wheel, said gearing including a worm in 95 mesh with the worm wheel and a gear loose on the starting shaft, a member carried by the loose gear and slidably thereon, an abutment on the second-mentioned clutch member 100 adapted to be intercepted by the member on the loose gear for turning said gear, and actuating means for said member.

5. In a starting device for internal-combustion engines, a starting shaft, a driving shaft, a spring connected to the driving shaft for turning the same, a spring-winding member loose on the driving shaft, a member fixed on the driving shaft, means for coupling 105 said member to the spring-winding member, a clutch member operatively connected to the second-mentioned member, a coöperating clutch member fixed on the starting shaft, a drive gearing between the starting shaft and the spring-winding member, and means for coupling 110 said gearing to the starting shaft and for uncoupling the same.

6. In a starting device for internal-combustion engines, a starting shaft, a driving shaft, a spring connected to the driving shaft for turning the same, a spring-winding member loose on the driving shaft, a member fixed on the driving shaft, means for coupling 120 said member to the spring-winding member, a clutch member operatively connected to the second-mentioned member, a coöperating clutch member fixed on the starting shaft, a drive gearing between the starting shaft and the spring-winding member, and means for coupling 125 said gearing to the starting shaft and the spring- 130

winding member, said gearing including a gear loose on the starting shaft, and means for coupling said loose gear to the starting shaft.

5. 7. In a starting device for internal-combustion engines, a starting shaft, a driving shaft, a spring connected to the driving shaft for turning the same, a spring-winding member loose on the driving shaft, a 10 member fixed on the driving shaft, means for coupling said member to the spring-winding member, a clutch member operatively connected to the second-mentioned member, a coöperating clutch member fixed 15 on the starting shaft, a drive gearing between the starting shaft and the spring-winding member, said gearing including a gear loose on the starting shaft, and means for connecting said loose gear to the second-mentioned clutch member.
8. In a starting device for internal-combustion engines, a starting shaft, a driving shaft, a spring connected to the driving shaft for turning the same, a spring-winding member loose on the driving shaft, a 20 member fixed on the driving shaft, means for coupling said member to the spring-winding member, a clutch member operatively connected to the second-mentioned member, a coöperating clutch member fixed 25 on the starting shaft, a drive gearing between the starting shaft and the spring-winding member, said gearing including a gear loose on the starting shaft, a member 30 carried by said loose gear and slidable thereon, an abutment on the second-mentioned clutch member adapted to be intercepted by the member on the loose gear for turning said gear, and actuating means for said 35 member.
9. In a starting device for internal-combustion engines, a starting shaft, a driving shaft, a spring connected to the driving shaft for turning the same, a spring-winding member loose on the driving shaft, a 40 member fixed on the driving shaft, means for coupling said member to the spring-winding member, a clutch member having a screw-threaded actuating connection with the second-mentioned member, a coöperating clutch member fixed 45 on the starting shaft, a drive gearing between the starting shaft and the spring-winding member, and means for coupling said gearing to the starting shaft and for uncoupling the same.
10. In a starting device for internal-combustion engines, a starting shaft, a driving shaft, a spring connected to the driving shaft for turning the same, a spring-winding member loose on the driving shaft, a 50 member fixed on the driving shaft, means for coupling said member to the spring-winding member, a clutch member having a screw-threaded actuating connection with the second-mentioned member, a coöperating clutch member fixed 55 on the starting shaft, a drive gearing between the starting shaft and the spring-winding member, and means for coupling said gearing to the starting shaft and for uncoupling the same.

11. In a starting device for internal-combustion engines, a starting shaft, a driving shaft, a spring connected to the driving shaft for turning the same, a worm wheel loose on the driving shaft, a member fixed 70 on the driving shaft, means for coupling said member and the worm wheel together, a clutch member having a screw-threaded actuating connection with the second-mentioned member, a coöperating clutch member fixed on the starting shaft, a drive gearing between the starting shaft and the worm wheel, said gearing including a worm 75 in mesh with the worm wheel, and means for coupling said gearing to the starting shaft and for uncoupling the same.

12. In a starting device for internal-combustion engines, a starting shaft, a driving shaft, a spring connected to the driving shaft for turning the same, a worm wheel loose on the driving shaft, a member fixed 80 on the driving shaft, means for coupling said member and the worm wheel together, a clutch member having a screw-threaded actuating connection with the second-mentioned member, a coöperating clutch member fixed on the starting shaft, a drive gearing between the starting shaft and the worm wheel, said gearing including a worm 85 in mesh with the worm wheel, and means for coupling said gearing to the starting shaft and for uncoupling the same.

13. In a starting device for internal-combustion engines, a starting shaft, a driving shaft, a spring connected to the driving shaft for turning the same, a spring-winding member loose on the driving shaft, a 90 slidable member carried by the spring-winding member and carrying a latch pin, a member fixed on the driving shaft and positioned to intercept the latch pin to couple said member and the spring-winding member together, means for operating the latch-carrying member, a clutch member operatively connected to the aforesaid member 95 which is fixed on the driving shaft, a co-operating clutch member fixed on the starting shaft, a drive gearing between the starting shaft and the spring-winding member, and means for coupling said gearing to the starting shaft and for uncoupling the same.

14. In a starting device for internal-combustion engines, a starting shaft, a driving shaft, a spring connected to the driving shaft for turning the same, a worm wheel loose on the driving shaft, a member fixed 100 on the driving shaft, means for coupling said member and the worm wheel together, a clutch member having a screw-threaded actuating connection with the second-mentioned member, a coöperating clutch member fixed on the starting shaft, a drive gearing between the starting shaft and the worm wheel, said gearing including a worm 105 in mesh with the worm wheel, and means for coupling said gearing to the starting shaft and for uncoupling the same.

15. In a starting device for internal-combustion engines, a starting shaft, a driving shaft, a spring connected to the driving shaft for turning the same, a worm wheel loose on the driving shaft, a member fixed 110 on the driving shaft, means for coupling said member and the worm wheel together, a clutch member having a screw-threaded actuating connection with the second-mentioned member, a coöperating clutch member fixed on the starting shaft, a drive gearing between the starting shaft and the worm wheel, said gearing including a worm 115 in mesh with the worm wheel, and means for coupling said gearing to the starting shaft and for uncoupling the same.

shaft for turning the same, a spring-winding member loose on the driving shaft, a member fixed on the driving shaft, means for coupling said member to and for uncoupling the same from the spring-winding means, actuating means for said coupling means, said actuating means including a slidable member, a spring connected to said slidable member for moving the same in one direction, a swinging arm operatively connected to the slidable member, a lever having means for engaging said arm to draw the aforesaid slidable member in another direction, a detent engageable with the arm for holding the slidable member against a return movement, a clutch member operatively connected to the aforesaid member which is fixed on the driving shaft, a coöperating clutch member fixed on the starting shaft, a drive gearing between the starting shaft and the spring-winding member, a clutch for said gearing, a slidable actuating member for said clutch, a spring connected to said slidable actuating member for moving the same in one direction, a cam for moving the slidable actuating member in another direction, a swinging member operating the cam and having a connection with the aforesaid arm to disengage the same from the detent, a rotatable member driven by the driving member and having an abutment, and an arm extending from the swinging member into the path of the abutment.

15. In a starting device for internal-combustion engines, a starting shaft, a driving shaft, a spring connected to the driving shaft for turning the same, a spring-winding member loose on the driving shaft, a member fixed on the driving shaft, means for coupling said member to and for uncoupling the same from the spring-winding means, actuating means for said coupling means, said actuating means including a slidable member, a spring connected to said slidable member for moving the same in one direction, a swinging arm operatively connected to the slidable member, a lever having means for engaging said arm to draw the aforesaid slidable member in another direction, a detent engageable with the arm for holding the slidable member against a return movement, a clutch member operatively connected to the aforesaid member which is fixed on the driving shaft, a coöperating clutch member fixed on the

starting shaft, a drive gearing between the starting shaft and the spring-winding member, a clutch for said gearing, a slidable actuating member for said clutch, a spring connected to said slidable actuating member for moving the same in one direction, a cam for moving the slidable actuating member in another direction, a swinging member operating the cam and having a connection with the aforesaid arm to disengage the same from the detent, a rotatable member driven by the driving member and having an abutment, and an arm extending from the swinging member into the path of the abutment.

16. In a starting device for internal-combustion engines, a starting shaft, a driving shaft, a spring connected to the driving shaft for turning the same, a worm wheel loose on the driving shaft, a member fixed on the driving shaft, means for coupling said member and the worm wheel together, a clutch member operatively connected to said member, a coöperating clutch member fixed on the starting shaft, a drive gearing between the starting shaft and the worm wheel, said gearing including a worm in mesh with the worm wheel, means for coupling said gearing to the starting shaft and for uncoupling the same, and means controlled by the driving shaft for timing the operation of both of the aforesaid coupling means.

17. In a starting device for internal-combustion engines, a starting shaft, a driving shaft, a spring connected to the driving shaft for turning the same, a spring-winding member loose on the driving shaft, a member fixed on the driving shaft, means for coupling said member to the spring-winding member, a clutch member operatively connected to the second-mentioned member, a coöperating clutch member fixed on the starting shaft, a drive gearing between the starting shaft and the spring-winding member, means for coupling said gearing to the starting shaft and for uncoupling the same, and means controlled by the driving shaft for timing the operation of both of the aforesaid coupling means.

In testimony whereof I affix my signature.

PHILIP POVLOTZKY.
